(57) CLAIM

(21) Appl. No.: **29/197,348**

The ornamental design for a soffit accessory strip vent with
semi-hidden vent, as shown and described in FIGS. 1-4.

(22) Filed: **Jan. 14, 2004**

DESCRIPTION

(51) LOC (7) Cl.: **23-04**

FIG. 1 is a front perspective view of the soffit accessory strip
vent with semi-hidden vent, showing our new design;

(52) U.S. Cl.: **D23/393**

FIG. 2 is a top planar view of the soffit accessory strip vent
with semi-hidden vent of FIG. 1;

(58) Field of Search: **D23/293, 386;**

FIG. 3 is a bottom planar view of the soffit accessory strip
vent with semi-hidden vent of FIG. 1; and,

52/94, 95; D25/119, 55, 19, 164, 61; 454/260,

FIG. 4 is a front elevational view of the soffit accessory strip
vent with semi-hidden vent of FIG. 1.
